UNITED STATES PATENT OFFICE.

GEORGE W. SNYDER, OF WESTERN COLLEGE, IOWA.

WEATHER-STRIP.

SPECIFICATION forming part of Letters Patent No. 309,580, dated December 23, 1884.

Application filed June 10, 1884. (No model.)

To all whom it may concern.

Be it known that I, GEORGE W. SNYDER, a citizen of the United States, residing at Western College, in the county of Linn and 5 State of Iowa, have invented certain new and useful Improvements in Weather-Strips, of which the following is a specification.

The object of my invention is to so construct a weather-strip for a door that it shall 10 automatically rise above the threshold as the door is opened, and close tightly upon it when the door is closed, performing the operations more perfectly, and by means of simpler mechanism, than any other weather-strip known to 15 me.

The invention consists in a strip of rubber cloth or other water-proof flexible material secured to a shaft pivoted to the door near the bottom, and connected with mechanism for 20 automatically turning it as the door is opened and closed, and also in a supplemental flap fastened to the door above this mechanism and overlapping the lower flap, for the purposes of protection and the complete exclusion of 25 water, as will be hereinafter more particularly set forth.

In the accompanying drawings, forming a part of this specification, Figure 1 represents an elevation of the lower part of a door with 30 the weather-strip attached; Fig. 2, a plan view of the same slightly ajar; Fig. 3, the detail of the mechanism for actuating the pivoted shaft, and Fig. 4 a cross-section of the invention in a vertical line.

35 Similar letters of reference indicate corresponding parts.

A strip, D, of flexible water-proof material, preferably rubber cloth, is secured to a small shaft of wood or metal, s, pivoted in 40 brackets e, fastened to the lower part of the door A and near the sides thereof.

For convenience in fastening the strip to the shaft, it is placed between the shaft and a metallic plate corresponding to the shape of 45 the shaft, and having holes at suitable distances for tacks or screws. This also renders the connection of the parts more close, uniform, and permanent. Between the shaft and the door is pivoted a lever, E, adapted to 50 turn the shaft by its vertical movement

through the medium of a hole or recess, i, made to loosely receive the end of a pin or lug, o, projecting from the back side of the shaft s. The lever E is preferably made thin and wide at its free end to give it weight, 55 and at the same time occupy as little room as possible. An arm extends vertically from the pivotal point and at a right angle to the body of the lever, and to this arm is connected a sliding rod, F, passing through the 60 upper part of the bracket e, and extending a short distance beyond it. This rod is designed to abut against the jamb C shortly before the door is closed, as shown in Fig. 2, and by its longitudinal movement raise the 65 lever E, which in turn rotates the shaft s and shifts the position of the flaps from that indicated by the dotted lines in Fig. 4 to full line, as it will be seen that as the door is closed, the flap is pressed downward upon the 70 threshold B, and as the door is opened the weight of the arm serves to raise it clear of the threshold and all obstructions. I prefer a weight to a spring by reason of its greater 75 certainty and durability, though it will be obvious that a spring would answer the purpose.

To prevent the water from running behind the lower flap already described, a supplemental flap, D', is secured to the door a suitable distance above the first, and overlaps it, as shown. This, as well as the former, is preferably provided with a metallic plate, v, through which tacks or screws are driven. I prefer to have these flaps of flexible material 85 rather than stiff and hinged, as they are better adapted to fit inequalities in the threshold and each other, and close over partial obstructions without leaving much, if any, opening for the admission of water. 90

I am aware that a weather-strip adapted to close down upon the threshold when the door is shut is not broadly new, and I do not claim such as my invention; but

What I do claim, and desire to secure by 95 Letters Patent, is—

1. The combination of flap D, shaft s, and lever E, substantially as and for the purpose set forth.
2. The combination of flap D, shaft s, le- 100

ver E, and sliding rod F, substantially as and for the purpose specified.

3. The combination of lower flap, D, shaft s, provided with pin or lug O, weighted le-
5 ver E, rod F, and upper overlapping flap, D', substantially as and for the purposes herein set forth.

In testimony whereof I affix my signature in presence of two witnesses.

GEORGE W. SNYDER.
